GARMENT HANGER CARRIER

Charles H. Borten, Towers of Windsor Park, Kyoto
Building, Suite 1-6, Cherry Hill, N.J. 08034

Filed Jan. 28, 1969, Ser. No. 15,543

Term of patent 14 years

Int. Cl. D8—03

U.S. Cl. D8—154

I claim:

The ornamental design for a garment hanger carrier, as shown and described.
